TONGS FOR MAIL BOX PICK-UP AND DELIVERY AND THE LIKE

Matthias W. Gudmundson, Mountain, N. Dak.

Filed July 12, 1963, Ser. No. 75,767

Term of patent 3½ years

(Cl. D54—13)

FIGURE 1 is a perspective view of tongs for mail box pick-up and delivery and the like showing my new design;

FIGURE 2 is a top plan view thereof;

FIGURE 3 is a side elevational view thereof;

FIGURE 4 is a bottom plan view thereof;

FIGURE 5 is a reverse side elevational view thereof, FIGURE 5 showing the jaws in their open position;

FIGURE 6 is an end elevational view thereof; and

FIGURE 7 is a reverse end elevational view thereof.

I claim:

The ornamental design for tongs for mail box pick-up and delivery and the like, as shown.
